Primary Examiner — Antoine Duval Davis(74) *Attorney, Agent, or Firm* — McAndrews Held & Malloy, Ltd.(57) **CLAIM**

The ornamental design for a wearable adhesive thermometer, as shown and described.

DESCRIPTION

FIG. 1 is a top perspective view of a wearable adhesive thermometer showing my new design;

FIG. 2 is a front elevation view thereof;

FIG. 3 is a rear elevation view thereof;

FIG. 4 is a right side elevation view thereof;

FIG. 5 is a left side elevation view thereof; and,

FIG. 6 is a top plan view thereof.

The broken lines in the drawings illustrate portions of the wearable adhesive thermometer that form no part of the claimed design.

The stipple shading in FIGS. 1 and 6 represents a contrast of appearance and does not represent any particular color, texture, or material.
